US00D858584S

(12) **United States Design Patent** (10) **Patent No.:** **US D858,584 S**
(45) **Date of Patent:** **** Sep. 3, 2019**

(54) **LIP SHROUD FOR A GROUND ENGAGING MACHINE IMPLEMENT**

(71) Applicant: **Caterpillar Inc.**, Deerfield, IL (US)

(72) Inventors: **Mihai Mircea Balan**, Dunlap, IL (US);
Douglas Serrurier, Morton, IL (US)

(73) Assignee: **Caterpillar Inc.**, Deerfield, IL (US)

(**) Term: **15 Years**

(21) Appl. No.: **29/663,270**

(22) Filed: **Sep. 13, 2018**

Related U.S. Application Data

(63) Continuation of application No. 29/615,660, filed on Aug. 30, 2017, now Pat. No. Des. 832,309.

(57) **CLAIM**

The ornamental design for a lip shroud for a ground engaging machine implement, as shown and described.

DESCRIPTION

FIG. 1 is a front perspective view of a lip shroud for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a second embodiment thereof;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

Grayscale shading represents contour.

The dashed broken lines illustrate structures or features which form no part of the claimed design.

The dot-dash broken lines illustrate boundaries which form no part of the claimed design.

1 Claim, 8 Drawing Sheets
